UNITED STATES PATENT OFFICE.

PHILLIP HIEN, OF ROCK ISLAND, ILLINOIS.

SEAL-LOCK FOR RAILROAD-CARS.

SPECIFICATION forming part of Letters Patent No. 324,691, dated August 18, 1885.

Application filed March 13, 1885. (No model.)

To all whom it may concern:

Be it known that I, PHILLIP HIEN, of Rock Island, in the county of Rock Island and State of Illinois, have invented certain Improvements in Seal - Locks for Railroad - Cars, of which the following is a specification.

The object of this invention is to provide a seal-lock which shall be at once simple, cheap, and durable, and which shall remain in an operative condition notwithstanding the severe strains to which it will be subjected and the changing position of the parts upon the car.

To this end it consists in the peculiar construction and arrangement of parts hereinafter described.

Referring to the drawings, Figure 1 represents a perspective view of my lock as it appears when applied to secure a car-door. Fig. 2 is a similar view showing the parts unlocked. Fig. 3 is a central vertical section on the line *x x* of the preceding figures. Fig. 4 is a cross-section on the line *y y* of Fig. 3.

Referring to the drawings, A represents the body of the car; B, the door arranged to slide horizontally in the usual manner; C, a hasp secured to the door and provided at its free end with a lip or shoulder, *a*; D, the case of the lock secured to the body of the car, and provided in its front face with a transverse groove or depression to receive the end of the hasp C, which is laid therein with its lip or shoulder *a* engaging over the outside of the lock-case; and E, a latch hinged at its upper end to the lock-case, and arranged to close in a downward direction over the end of the hasp C, for the purpose of holding the same in engagement.

For the purpose of locking or securing the latch I mount within the lock-case a vertical gravitating bolt, F, the lower end of which is adapted to enter a hole in the upper surface of a tang or lip, *c*, which is formed on the lower end of the latch, and which on the latch being closed passes beneath the lower end of the case, as shown in Fig. 3. The latch in closing acts to lift the bolt, which engages therein in the manner represented in Fig. 3.

In order to prevent the bolt from being improperly released, the lock-case is provided immediately in front of the bolt with an opening adapted to receive a glass or other appropriate seal or covering, I, which is confined in posi-

tion by means of the latch closing over and around its upper edge. The edges of the opening are shouldered or rabbeted, as shown at *i*, 55 to form a seat or bearing for the edges of the seal. The latch is provided, as shown, with an opening through which the glass is exposed, in order that it may be broken when desired, and through which access may be had to the bolt 60 in order to lift the same for the purpose of releasing the latch when the door is to be opened.

It will be seen that the seal is confined in such manner that access to the bolt is impossible unless the seal be first destroyed. 65

In order that the fragments of the seal may readily escape from the interior of the lock-case, so that the operation of the bolt may not be prevented thereby, I provide the case at its bottom with an opening, *d*, for the passage of 70 the fragments. The interior of the case is inclined backward and downward toward this opening to facilitate the discharge of the fragments. When the latch is closed, its lower end covers and closes the opening *d*, in the manner 75 represented in Fig. 3, thus preventing access to the interior of the lock-case at improper times.

As an additional means of securing the parts in a locked position, I provide the lock-case 80 D with a perforated ear, *f*, adapted to extend outward through a slot, *g*, in the latch, and to receive a padlock or equivalent fastening device. This provision admits of the lock being secured by means of the sealed bolt or of the 85 padlock, or of both, as occasion may require.

It will be perceived that the lock constructed on my plan is of exceeding simplicity, and that the construction admits of the hasp being brought to its place and secured, notwithstanding the springing, shifting, or twisting of the parts which commonly occurs in railroad-cars, and which frequently prevents the parts from being brought with certainty to the accurate position demanded by other locks. 95

Having thus described my invention, what I claim is—

1. The lock-case provided with the hinged latch, the gravitating bolt, and the seal-receiving cavity, in combination with the hasp provided with the lip or shoulder. 100

2. In a seal-lock for railroad-cars, the lock-case provided with the transverse recess in its face, in combination with the swinging hasp

C, adapted to lie freely in said recess, and provided with the lip *a* to engage the exterior of the case, the latch E, hinged to the case to overlie the hasp, and the gravitating bolt F, adapted to engage the lip of the latch.

3. In a seal-lock for cars, the lock-case having the internal chamber with a seal-receiving seat at the front, and a seal-discharging hole, *d*, at the bottom, in combination with the gravitating bolt in said chamber, and the latch E, provided with the lip *c*, adapted to extend beneath said lock-case for the double purpose of engaging the bolt and closing the hole *d*, as described and shown.

15 4. In a seal-lock for cars, the lock-case provided with the vertical gravitating bolt, the hasp-receiving and the seal-receiving recesses, in combination with the hinged latch overlying the said recesses and adapted to interlock with the lower end of the bolt, as described and shown.

ing the said recesses and adapted to interlock with the lower end of the bolt, as described 20 and shown.

5. The lock-case provided with the seal-receiving cavity, the external recess to admit the hasp C, and the perforated ear *f*, in combination with the internal gravitating bolt and the 25 hinged latch E, having the lip *c* to engage the bolt, and the slot *g* to receive the ear, whereby the device is adapted to be secured by a sealed bolt and a padlock, or either one, at will.

In testimony whereof I hereunto set my hand 30 this 5th day of March, 1885, in the presence of two attesting witnesses.

PHILLIP HIEN.
